UNITED STATES PATENT OFFICE.

FRANK F. TRIPP, OF ROXBURY, MASSACHUSETTS.

SELF-SEATING VALVE.

1,125,606.

Specification of Letters Patent. Patented Jan. 19, 1915.

Application filed June 26, 1913. Serial No. 776,433.

To all whom it may concern:

Be it known that I, FRANK F. TRIPP, a citizen of the United States of America, and a resident of Roxbury, in the county of Suffolk and State of Massachusetts, have invented certain new and useful Improvements in Self-Seating Valves, of which the following is a specification.

This invention relates to valves and particularly to that class of valves that move about a pivot against the end of a pipe, the object of the present invention being to provide means whereby the valve will always accurately seat when moved about its pivot into contact with the pipe end.

The invention consists primarily in providing the valve with a tilting disk balanced on a central projection extending upwardly from a bottom plate, said disk being adapted to move on said projection to accommodate itself to the plane of the valve seat.

The invention further consists in certain novel features of construction and arrangement of parts which will be fully understood by reference to the description of the drawings and to the claims hereinafter given.

Of the drawings: Figure 1 represents a vertical section of a device embodying the features of the present invention. Fig. 2 represents an enlarged section of the valve itself, and the end of the pipe which it is intended to close. Fig. 3 represents a plan view of said valve, and Fig. 4 represents a plan of the blank from which the chambered portion of the valve is formed.

Similar characters designate like parts throughout the several figures of the drawings.

In the drawings, 10 is a pipe to the end of which is threaded a casing 11 having a chamber 12 therein. The lower end of this casing member 11 is provided with an outlet boss 13 to which is threaded a discharge pipe 14. In the end of the pipe 10 is a nipple 15 extending into the chamber 12 and having its outer periphery beveled off to form a suitable valve seat. Extending laterally of the chamber 12 is a pin or stud 16 on which is mounted the member 17 having a weight 18 at one end and having se-

cured to its opposite upper face a chambered member 19. This chambered member 19 is formed of a blank such as is shown in Fig. 4 of the drawing, consisting of a bottom plate 20 and a plurality of extensions 21 subsequently bent upwardly as at 22 and inwardly as at 23, thus forming a means for positioning the self-seating disk 24 resting upon a central projection 25 extending upwardly from the bottom plate 20. The disk 24 is covered with leather or some other yielding material 26 held in position on the disk 24 by means of a ring 27, which is semi-cylindrical in cross section. Normally the disk 24—26—27 is balanced on the upward extension 25 and prevented from displacement by means of the inward projections 23. As the member 17 moves about its pivot 16 the disk 24 is adapted to tilt upon the end of the projection 25 to accommodate itself to the plane of the seat on the end of the pipe nipple 15 so that an accurate closing will always be assured.

Any inequalities in the edge of the valve seat will be cared for by the yielding covering 26 to the disk 24. The periphery of the retaining ring 27 of the disk 24 is curved to facilitate the tilting of said disk, obviating any liability to cramp in the tilting movement against the uprights 22. This makes a very simple and convenient form of self-adjusting valve which may be manufactured at little expense.

It is believed that the operation and many advantages of this invention will be fully understood from the foregoing description.

Having thus described my invention, I claim:

1. A device of the class described, comprising a valve seat, a closing disk to coact therewith, and a disk-retaining member formed from sheet metal having a plurality of disk retaining fingers and an embossed central pivotal point pressed up from said metal to support the disk.

2. A device of the class described, comprising a valve seat, a valve closing disk, a leather face therefor, a ring of semi-circular cross section having a thickness equal to the thickness of the disk and leather adapted to

clamp the edge of said leather face to the edge of said disk, and a disk retaining member formed from a single piece of sheet metal having radial fingers bent up to loosely embrace the disk and a centrally disposed projection pressed up from the metal to form a supporting point for the disk.

Signed by me at Boston, Mass., this 12th day of June, 1913.

FRANK F. TRIPP.
